MANUAL TELEPHONE EXCHANGE

Wilfried Klenk and Erich Behm, Berlin, Germany,
assignors to Mix & Genest Aktiengesellschaft,
Berlin-Schöneberg, Germany, a company

Application January 18, 1939, Serial No. 251,568
In Germany January 17, 1938

9 Claims. (Cl. 179—91)

The invention relates to cordless manual exchange equipments for telephone systems or the like and has for its object to improve the manufacture of these equipments and to reduce the cost thereof. To such end the invention mainly aims to simplify the jack multiple of such devices.

With these objects in view the invention consists in certain features of novelty which will appear from the following description, reference being had to the accompanying drawings, in which

Fig. 1 shows an example of a circuit arrangement suitable for exchange devices as provided by the invention. Fig. 2 is a front elevation of one embodiment of such devices. Fig. 3 is a fragmentary plan of this embodiment. Fig. 4 shows a section on line 4—4 of Fig. 2. Figs. 5 and 6 are fragmentary representations of two plates used for assembling a grid-shaped structure more fully referred to hereafter. Fig. 7, drawn to a larger scale than Fig. 2, shows a section on line 7—7 thereof. Fig. 8 is a fragmentary front elevation representing a second embodiment of the invention. Fig. 9 shows a section on line 9—9 of Fig. 8. Fig. 10 a partial section on line 10—10 of Fig. 9. Fig. 11 represents one of the contact strips used in the arrangement to which Figs. 9 and 10 refer. Fig. 12 illustrates in perspective a slight modification of the jack shown in Figs. 9 and 10. Fig. 13 is a fragmentary perspective view of two contact strips intended for jacks constructed in accordance with Fig. 12. Fig. 14 illustrates in perspective a plug suitable for jacks of the latter kind. Fig. 15 represents a section on line 15—15 of Fig. 14.

The arrangement shown in Fig. 1 comprises rest jacks P, answering jacks Q, and junction jacks R. Terminals $a_1, b_1 \dots a_X, b_X$ of lines 3 are for the junction of the subscribers' stations designated I to X. One pair of lines 3 has terminals a_O, b_O for the connection of an office O, for instance. By $K_O, K_I \dots K_X$ drop indicators of well known type are denoted, which have make contacts $k_O, k_I \dots k_X$. W indicates a ringer whose circuit contains lines L_1, L_2 in bridge of which the contacts $k_O, k_I \dots k_X$ are connected. SO, SI . . . SX denote plugs, shown to be inserted in the jacks P and adapted to be inserted in any of the jacks Q, R in order to join the lines 3 to lines 3' arranged at right angles to the former. By J the operator's magneto is designated. Drop indicators $K'_I \dots K'_X$, having each a make contact $k'_I \dots k'_X$, are in well known manner under the control of

the subscribers' magnetos. Each of the jacks P, Q, R has four springs p, q, r , respectively, adapted to contact in pairs with two metal rings 13, 14 with which each of the said plugs is provided.

If subscriber I desires a connection to be established he removes his handset and actuates his magneto, whereby indicator K_I drops its armature or flap, thus closing contact k_I . The following circuit is established thereby: +, $L_1, k_I, L_2, W, -$. The operator's ringer W is hence actuated. The dropped flap indicates to the operator who of the subscribers is calling. The operator then restores indicator K_I to normal, withdraws plug SI from that jack P which belongs to the subscriber's station I and inserts this plug in that answering jack Q which is joined to the same lines $3, a_1$ and $3, b_1$ as the said jack P. By restoring the indicator K_I to normal, contact k_I is opened, thus disconnecting the ringer W. The operator by means of her telephone now enquires the calling subscriber as to his wish. If he desired to speak to subscriber X, for instance, the operator removes plug SI from jack Q in order to insert it in one of those jacks R whose lines 3' are not busy and which are joined to the lines $3, a_1$ and $3, b_1$. She then removes plug SX from jack P allotted to station X and inserts this plug in jack Q joined to the lines $3, a_X$ and $3, b_X$. The operator now calls subscriber X by means of her magneto J. If he answers, plug SX is inserted in that jack R which is joined to the lines $3, a_X$ and $3, b_X$ and joined also to the same lines 3' with which the aforesaid jack R has been connected. The stations I, X have thus become interconnected.

At the end of the conversation one of the subscribers will actuate his magneto thus causing the indicator belonging to those lines 3' which have been engaged in the manner just described, such as indicator K'_I , for instance, to drop its flap or armature, whereby contact k'_I closes a circuit for ringer W. The operator thereby knows that the conversation has been finished. She therefore restores this flap to normal and also withdraws the plugs SI, SX from the said jacks R in order to insert them again in the respective jacks P.

The circuit arrangement represented in Fig. 1 may be constructed in the manner now explained with reference to Figs. 2 to 7. The jacks P, Q, R are here formed as cavities of a grid-shaped structure B composed of insulating plates 2, 2' carrying the contact springs p, q, r shown also in Fig. 1. The plates 2 have slots c in which the plates 2' are inserted. Equally, the plates 2' are

provided with slots *c'* in which the plates **2** are seated, as will be seen from Fig. 7. The springs *p*, *q*, *r* are secured to the plates **2**, **2'** by rivets **4**, for example. The springs *p* are in part separate from one another, as is required in the arrangement disclosed in Fig. 1. The springs *q*, *r* are projections of the contact strips **3**, **3'**. All these springs reach into the cavities of the structure **B** through apertures **29** provided in the plates **2**, **2'**.

In the embodiment shown in Figs. 8 to 11 the jacks **P**, **Q**, **R** each comprise an insulating socket **8** and the contact springs *p*, *q*, *r*, respectively. The sockets **8** are mounted in a board **10**. The contact strips that correspond to the strips **3**, **3'**, Fig. 2, are designated **3a**, **3a'**. In distinction from the strips **3**, **3'** the strips **3a**, **3a'** are each provided with two springs *q* or *r* for each jack, as will appear from Fig. 11. Strip **3a** here shown has circular openings **35** from the edge of which the springs *q* or *r*, as the case may be, are bent outward. The strips **3a'**, only represented in Figs. 9 and 10, are of the same construction as the strips **3a**. The openings **35** serve to insert the strips **3a**, **3a'** over the sockets **8**. The strips **3a** are in this way arranged at right angles to the strips **3a'** and are separated from each other by insulating discs or bushes **30**. The jack springs, such as springs *q* shown in Fig. 9, project through slots **11** of the sockets **8**. The parts **3a**, **3a'**, **30** are held in place by insulating hooks **17** fixed to the sockets **8** by means of a screw **18** each. The hoods **17** are dust-proof and humidity-proof.

The plugs suitable for the arrangement shown in Figs. 8 to 11 may be the same as the plugs **SO**, **SI** . . . **SX**, Fig. 1.

As illustrated in Fig. 12, the jack sockets, here designated **8'**, may be rectangular in cross section, the strips **3a**, **3a'** having rectangular openings **35'** in lieu of the circular openings **35** shown in Fig. 11. In distinction from the construction represented in Figs. 9, 10, 11 the strips **3a**, **3a'** each have merely one spring *q* concerned in the formation of each jack **Q**, or, in the case of the jacks **R**, Fig. 1, merely one jack spring *r*, the arrangement being in this regard similar to that illustrated in Figs. 2 to 7.

The plugs **S** adapted for use in connection with jacks **8'** are rectangular in cross-section as shown in Fig. 14. The plug here represented by way of example has four contact pieces or segments **25**, **26** instead of the contact rings **13**, **14** of the plugs shown in Fig. 1. This plug in the case of a double jack enables four circuits to be switched jointly.

In all the constructions here disclosed the plugs are guided by jack springs arranged in pairs to oppose each other, whereby a perfect contact effect is insured while the plugs are prevented from slanting.

What is claimed is:

1. A telephone exchange comprising a plurality of pairs of flat metal strips disposed alongside each other and substantially parallel, a second plurality of pairs of flat metal strips dis-

posed alongside each other substantially parallel to one another and crossing said first plurality of pairs of strips, a first plurality of resilient lugs at least one per pair of strips of said second plurality formed integrally from each strip of said first plurality, a second plurality of resilient lugs at least one per pair of strips of said first plurality formed integrally from each strip of said second plurality, an insulating structure carrying said metal strips and forming openings for the insertion of contact plugs, at least one lug of said first plurality of lugs and at least one lug of said second plurality of lugs extending into each of said openings, and a plurality of contact plugs shaped for insertion in said openings and comprising conductive members for interconnecting said lugs.

2. A telephone exchange according to claim 1, wherein the said structure is grid-shaped and composed of a set of insulating plates provided with slots and another set of insulating plates likewise fitted with slots, the plates of each such set being seated in the slots of the other set.

3. A telephone exchange according to claim 1, wherein the said structure is grid-shaped and composed of insulating plates carrying the said flat metal strips and lugs, these lugs reaching through said plates into the spaces therebetween.

4. A telephone exchange according to claim 1, wherein the said structure comprises a board and jack sockets mounted therein, such sockets carrying the said flat metal strips and lugs.

5. A telephone exchange according to claim 1, wherein the said structure comprises a board and jack sockets mounted therein, such sockets being of insulating material and carrying the said flat metal strips and lugs.

6. A telephone exchange according to claim 1, wherein the said structure comprises a board and insulating jack sockets mounted therein and carrying the said flat metal strips and lugs, such sockets having slots for these lugs to project into the interior thereof.

7. A telephone exchange according to claim 1, in which the said structure comprises a board and jack sockets mounted therein, such sockets carrying the said flat metal strips and lugs and having slots through which these lugs reach into the interior of these sockets and a tightly fitting hood at the rear end of each such jack.

8. A telephone exchange according to claim 1, in which the said structure comprises a board and jack sockets mounted therein and carrying the said flat metal strips and lugs, such sockets and said plugs being of oblong rectangular cross-section.

9. A telephone exchange according to claim 1, in which the said structure comprises a board and jack sockets mounted therein and carrying the said flat metal strips and lugs, these sockets and said plugs being of oblong rectangular cross-section, each plug comprising an insulating body and contact segments provided therein.
